UNITED STATES PATENT OFFICE.

ABEL M. RAWSON, OF SAN FRANCISCO, CALIFORNIA.

HYDRAULIC-MINING ENGINEERING METHOD AND APPARATUS.

SPECIFICATION forming part of Letters Patent No. 486,897, dated November 29, 1892.

Application filed May 28, 1892. Serial No. 434,816. (No model.)

To all whom it may concern:

Be it known that I, ABEL M. RAWSON, of San Francisco, in the county of San Francisco and State of California, have invented certain new and useful Improvements in Methods of and Apparatus for Hydraulic Mining; and I do hereby declare the following to be a full, clear, and exact description of the invention, such as will enable others skilled in the art to which it appertains to make and use the same.

My invention relates to improvements in hydraulic mining; and its object is to retain in the gorges in which such mining operations are conducted the débris from such operations which would otherwise be carried down into the valleys below and cause great damage therein; and my invention consists more particularly in the methods and apparatus hereinafter specified, and set forth in the claims.

In the accompanying drawings, Figure 1 is a plan view of part of a gorge, showing my improved apparatus and the mode of using the same. Fig. 2 is a longitudinal sectional view of the same in the earlier stages of the process, and Fig. 3 is a similar view in the later stages thereof.

Having first selected a suitable location in the gorge at such a distance below the field of mining operations as will permit of the deposition of the débris which may be expected to result therefrom, a stone dam A is built across the gorge of about sixteen feet in height and of sufficient strength to resist the pressure of a volume of water rising to its crown with catch-basins B, placed against its upper face, opening five feet from the base of the dam. The area of these catch-basins on a horizontal section should be at least six times that of the water-conduits in use in mining, thus giving ample facility for the permeation of water through the débris.

C are pipes perforating the dam and connecting with the catch-basins and should be placed at a distance of not less than four feet below the crown of the dam.

D is a large pipe or covered flume which may run under, through, or by either end of the dam, its upper end being at the first operation upon a level point with the pipes C. As the deposition of débris proceeds additional sections are added on at the upper end of the pipe. The object of this pipe is to

carry off the clear water resting above the upper sloping surface of the débris last deposited.

55

E is a relief pipe, flume, or ditch, which conveys the stream of the gorge and all water intended for mining purposes when not in use beyond the dam. This pipe is used when for some cause it is not desired to use the clear-water pipe, as when it is necessary to clean the catch-basins B. The first operation after the construction of the dam is completed is to fill the catch-basins B with débris to the proper height. This may be accomplished by the ordinary action of the process of hydraulic mining, which impels the débris, mingled with water, down the channel of the gorge until it is arrested in the catch-basins, provided that care is taken that the first deposits in the catch-basins be of such a character—as clear gravel—as will permit of free percolation therethrough. The gravel in the catch-basins will rise to a height h , while the clear water will rise to the level of the perforating-pipes 70 C and will be carried off through these pipes. After the débris deposited in the gorge above the dam has reached a point parallel with the opening of the clear-water pipe D it is necessary to have recourse to the elevated flume 80 E'. This flume should be adjustable at such a point above the clear-water pipe D as will give the necessary pitch to discharge the mingled water and débris (marked m in the drawings) at least forty feet below it; but in the earlier stages of the process it is necessary to add to the main flume E' distributing branches F in order to distribute the mingled débris and water evenly at different points transversely of the gorge, otherwise a 90 full stream of mingled gravel and water pouring on toward the dam and confining itself to a single channel would continue to deposit the débris in the same location, so that its channel would be raised until in time its banks 95 would be above the level of the crown of the dam and the water would flow over the dam, there not being sufficient percolating-surface in a single channel to allow the water to sink into the control of the dam and be drawn 100 away by the catch-basins and their connecting-pipes. By dividing this flow into smaller streams distributed in an arc of a circle sufficient percolating-surface would be com-

passed to allow the water to find its level, leaving the débris distributed near the point of its fall from the distributing branches F. When, however, the dry barrier (marked d) 5 becomes of sufficient strength to resist the force of the full stream, the use of the distributing branches may be discontinued, as shown in Fig. 3; but in this case the direction and point of discharge of the service-flume E' 10 should be made adjustable so as to permit the even deposition of the débris over the entire space between the sides of the gorge and up to the level of its discharge; also, when this point in the operation has been reached and 15 when the dry barrier has become sufficiently strong to resist the force of the full stream all manner of débris, sedimentary or otherwise, may be thrown against the barrier, which, as its density increases, will repel the 20 greater portion of the water, which will rise behind the slope of the barrier until the surface of the water comes above the opening of the clear-water pipe D, which will thus carry off nearly all of the water used, leaving the 25 débris deposited upon the slope of the barrier and upon the bottom of the gorge. As the barrier approaches the opening of the pipe other sections can be added thereto and the lower section of the flume E' removed and 30 conveyed to its upper end for future use when required. This process can be repeated until the barrier reaches that point in the gorge where the mining operations were conducted. The width of the gorge having been increased 35 by such mining operations, this permits of a larger area to receive the deposits of mining operations carried on at a higher point in the gorge, and such deposits will occupy the place of the débris previously removed in earlier 40 operations.

Having thus fully described my invention, what I claim, and desire to secure by Letters Patent, is—

1. In an apparatus for hydraulic mining in 45 gorges, the combination of a dam extending across the gorge below the mining operations with a pipe or conduit extending longitudinally of the gorge, its receiving end being above the dam and its discharging end below 50 the same, and additional pipe-sections adapted to be secured at the upper end of said pipe to extend the same as required, substantially as described.

2. In an apparatus for hydraulic mining in 55 gorges, the combination of a dam extending across the gorge below the mining operations with a pipe or conduit extending longitudinally of the gorge, its receiving end being above the dam and its discharging end below 60 the same, and an elevated supply flume or conduit discharging above said dam, substantially as described.

3. In an apparatus for hydraulic mining in 65 gorges, the combination of a dam extending across the gorge below the mining operations with a pipe or conduit extending longitudi-

nally of the gorge, its receiving end being above the dam and its discharging end below the same, and an elevated sectional supply flume or conduit discharging above said dam, 70 substantially as described.

4. In an apparatus for hydraulic mining in gorges, the combination of a dam extending across the gorge below the mining operations with a pipe or conduit extending longitudinally of the gorge, its receiving end being above the dam and its discharging end below the same, an elevated supply flume or conduit, and distributing branch flumes discharging above the dam, substantially as de- 80 scribed.

5. In an apparatus for hydraulic mining in gorges, the combination of a dam extending across the gorge below the mining operations with catch-basins open at the bottom abut- 85 ting against the face of the dam, said dam having perforations leading from the catch-basins, substantially as described.

6. In an apparatus for hydraulic mining in gorges, the combination of a dam extending 90 across the gorge below the mining operations with catch-basins open at the bottom abut-ting against the face of the dam, said dam having perforations leading from the catch-basins, and a pipe extending longitudinally 95 of the gorge, its receiving end being above the dam and its discharging end below the same, substantially as described.

7. In an apparatus for hydraulic mining in gorges, the combination of a dam extending 100 across the gorge below the mining operations with catch-basins open at the bottom abut-ting against the face of the dam, said dam having perforations leading from the catch-basins, a pipe extending longitudinally of the 105 gorge, its receiving end being above the dam and its discharging end below the same, and an elevated supply flume or conduit and distributing branch flumes discharging above the dam, substantially as described. 110

8. In an apparatus for hydraulic mining in gorges, the combination of a dam extending across the gorge below the mining operations with a pipe or conduit extending longitudinally of the gorge, its receiving end being 115 above the dam and its discharging end below the same, an elevated supply flume or conduit discharging above said dam, and a relief pipe discharging below said dam, substan-tially as described. 120

9. In hydraulic mining in gorges, the pro-cess which consists in arresting mingled débris and water resulting from the mining op-erations, permanently retaining the earthy matter in the gorge, while allowing the water 125 to flow down into the valley below, the above steps of the process being accomplished by artificial means, substantially as and for the purpose set forth.

10. In hydraulic mining in gorges, the arti-130 ficial process which consists in arresting the mingled débris in the water resulting from

mining operations, permanently retaining the earthy matter to form a barrier across the gorge, discharging the mingled débris and water upon the barrier, and carrying off the 5 clear water which accumulates above said barrier, substantially as and for the purpose set forth.

In testimony whereof I have signed this specification in the presence of two subscribing witnesses.
